UNITED STATES PATENT OFFICE

2,358,025

RAILWAY CAR SIDE DOOR LOCK

Karl F. Nyström, Milwaukee, Wis., assignor to
Standard Railway Equipment Manufacturing
Company, a corporation of Delaware

Original application April 21, 1941, Serial No.
389,487, now Patent No. 2,349,014, dated Janu-
ary 25, 1944. Divided and this application
December 20, 1941, Serial No. 423,709

2 Claims. (Cl. 292—63)

This invention relates to side doors for railway cars and more particularly to railway cars having a great inside width while falling within the maximum outside width defined by the clearance lines which are specified by the Association of American Railroads. Railway cars commonly have doorways in the side walls thereof and doors for closing such doorways are commonly movable in planes substantially parallel with the side walls of the car. The necessary characteristics of such doors are that they be strong enough to resist thrusts from the inside of the car caused by the shifting of the lading and that they form reasonably tight seals with the frame members around the doorways to prevent the entrance of moisture, cinders and other foreign matter into the interior of the car.

An object of the invention is to provide a lock which permits the door to be moved freely to full closed position without any necessity for manipulating the locking mechanism during such closing movement. The door is not automatically locked by the closing movement thereof but is in position to be securely locked by a subsequent simple operation.

Another object of the invention is to provide a door lock which does not interfere with sealing strips on the edges of the door and doorway frame, which method of accomplishing such means will be hereinafter pointed out in detail.

Other objects and advantages of my invention will be apparent from the following detailed description by referring to the accompanying drawings.

In the drawings:

Fig. 1 is a side elevation of a portion of a railway car showing a side door embodying my improved lock.

Fig. 2 is an enlarged view of the lock mechanism shown in Figure 1, the door being fully closed and locked.

Fig. 3 is a view of the lock mechanism shown in Fig. 2 when the door is in full closed position but not locked.

Fig. 4 is a section on line 4—4 of Figure 2.

Figure 1 discloses a portion of a railway car having the usual side plate 2, side sill 3 and vertical posts, such as the door posts 5, 6, extending between and secured to the plate 2 and sill 3. The present invention is particularly related to the door and doorway structure of the car; the other parts of the side wall may be of any convenient design such as, for example, that shown in my Patent No. 2,150,897 dated March 21, 1939.

The door 8 has front 10 and rear 11 roller

5 housings rigidly secured thereto with rollers 13 revolubly mounted within the housings. The door track 14 is a channel member having its web secured to the outer side of the web 16 of the channel shaped sill 3 and with its lower flange 17 supporting the tread which is an angle 19 upon which the rollers 13 roll during horizontal movement of the door 8. The lower flange 17 is coped so that the tread angle 19 may be depressed 20 at certain places below the general level of the tread. The depressions 20 in the tread 19 are arranged so that when the door 8 is in the full opened or full closed position, the rollers 13 are above the depressions 20 and the weight of the door is taken by the bottom frame strip of the door engaging a projection on the track, thereby frictionally resisting movement of the door. The rollers 13 are then out of engagement with the tread 19 and may be rotated freely. 15 When the door 8 is in any position between full opened and full closed, the rollers 13 engage the undepressed parts of the tread 19 and the door moves freely in a horizontal direction. In order to overcome the above mentioned frictional resistance and move the door 8 into such position that the rollers are operative, a starting lever 24 is pivotally mounted upon the door 8, which lever 24 has a projection 25 on the lower end thereof arranged to engage a starting bracket 27 secured 20 to the side sill 3 so that a leverage may be exerted to pry the door 8 into rolling position. The operation of the starting lever 24 is more fully explained in Schlesinger Patent No. 1,963,152 dated June 19, 1934. 25

30 The locking mechanism 30 for the door 8 is comprised of a bracket 31 rigidly mounted, preferably by means of rivets 33, upon the side sill 3 of the car and arranged to extend upwardly and outwardly therefrom. The upper part of the bracket 31 carries a pair of spaced apart lugs 34, 36 having aligned holes therethrough and a rigid pin 37 is inserted through both holes and held in place by a cotter key 39. A latch member 40 has a vertically extending slot 42 therethrough 35 and the pin 37 projects through the slot 42 so that the latch member 40 is slidable vertically to an extent limited by the length of the slot 42. The latch member 40 is also free to rotate upon the pin 37 as a fulcrum, which rotation is limited 40 by the parts 43, 45 of the bracket 31.

45 The front roller housing 10 has a nose 47 which protrudes beyond the front edge 48 of the door 8 and has a vertically extending hole 50 therethrough or upwardly facing recess therein. 50

55 When the door 8 is in the full closed and locked

position, as shown in Figure 2, the lower end 51 of the latch member 40 is disposed in the hole 50 in the roller housing nose 47 and thereby prevents horizontal movement of the door 8. The latch member 40 is provided with an outwardly projecting lug 53 and a dog 54 is pivotally mounted upon the pin 37 and also provided with an outwardly projecting lug 56 aligned with the lug 53 when the lock is in the locked position, as shown in Figure 2. The lug 56 has a hole 57 arranged to align with the hole 59 in the latch member lug 53 when the lock is in the position shown in Figure 2. The latch member 40 is thus prevented from moving vertically and the door 8 is, therefore, locked in the full closed position. A seal may be inserted through both the holes 57, 59 so that any unauthorized opening of the door 8 may be detected by railroad officials, or others responsible for maintaining the car in the sealed condition.

When the door 8 is in an opened position, both the latch member 40 and the dog 54 hang by their own weight in depending positions. When door 8 is moved to the full closed position as shown in Figure 3, the latch member 40 rotates about the pin 37 to the position shown. In order to lock the door 8, it is necessary to rotate the dog 54 until the lug 56 thereof is moved out of the path of the lug 53 on the latch member 40; then the latch member 40 may be moved upwardly and then downwardly until the lower end 51 thereof is inserted in the hole 50 through the nose 47 of the roller housing 10. The dog 54 is then rotated to the position shown in Figure 2 and the seal may be inserted through the holes 57, 59 for the purpose of sealing the door. In order to open the door, the above described operation is performed in reverse.

The accompanying drawings illustrate the preferred form of the invention, though it is to be understood that the invention is not limited to the exact details of construction shown and described, as it is obvious that various modifica-

tions thereof, within the scope of the claims, will occur to persons skilled in the art.

This is a division of my application filed April 21, 1941, Serial No. 389,487, now Patent No. 2,340,014, dated January 25, 1944.

I claim:

1. In a railway car having a side wall, a doorway in said side wall and a door movable in a plane parallel with said wall for closing said doorway, the combination of a bracket secured to said wall, a latch mounted upon said bracket and arranged for limited vertically slidable and rotating movement in a plane substantially parallel with said wall, a lug on said latch, a member fixedly secured to said door having a lateral protrusion below said doorway extendable in the path of said latch when in its lowermost position, said protrusion having a vertically extending aperture aligned with said latch when in its lowermost position and when the door is closed, and a dog unrestrainedly pivotally mounted on said bracket and arranged to be moved into alignment with said lug to prevent upwardly sliding movement of said latch.

2. In a railway car having a wall, a doorway in said wall, and a door movable in a plane parallel with said wall for closing said doorway, the combination of a bracket secured to said wall, a latch, means to mount said latch upon said bracket for limited pivotal and vertically slidable movement, a lug carried by said latch, a dog mounted upon the bracket by said means for substantially unrestricted pivotal movement, said dog engageable with said lug to prevent vertical movement of the latch during any pivotal position of the latch, said dog being pivotally swingable out of engagement with the lug to permit vertical movement of the latch, and a member mounted upon said door having a hole therein, said hole being in alignment with said latch when the door is in substantially closed position so that the door may be locked by passing said latch through said hole.

KARL F. NYSTROM.
